UNITED STATES PATENT OFFICE

FRANK SUMNER GRIFFIN, OF WEST PALM BEACH, FLORIDA

TORCH

Application filed September 4, 1931. Serial No. 561,238.

This invention relates to gasoline torches.

An object of the invention is the provision of a compact unitary structure having a barrel forming the storage chamber for fuel and a handle for supporting the torch while in operation.

A further object of the invention is the provision of a torch having a centrally disposed barrel forming a storage chamber for fuel with means at one end for atomizing the fuel while means is employed at the opposite end of the barrel for providing an intense flame.

This invention will be best understood from a consideration of the following detailed description, in view of the accompanying drawing forming a part of the specification: nevertheless it is to be understood that the invention is not confined to the disclosure, being susceptible of such changes and modifications which shall define no material departure from the salient features of the invention as expressed in the appended claims.

In the accompanying drawing:

Figure 1 is a vertical longitudinal section of a torch constructed in accordance with the principles of my invention;

Figure 2 is a longitudinal side view of the torch;

Figure 3 is a transverse vertical section, taken along the line 3-3 of Figure 1;

Figure 4 is a transverse vertical section, taken along the line 4-4 of Figure 1.

Referring more particularly to the drawing, 10 designates a cylindrical barrel providing a storage chamber for fuel, which has one end enclosed by means of a removable plug 11 and the other end closed by a removable head 12.

A tube 13 extends axially and longitudinally through the barrel 10 and has one end, as shown at 14, threaded into a passage or mixing chamber 15 of the head 12. The opposite end of the tube extends through the plug 11 and is threaded, at 16, into a burner 17.

The burner is cylindrical in form and is provided with a diagonal slot 18 at one end which is adjacent to the connection between the tube 13 and the burner 17. Mounted on

the outer open end 19 of the cylindrical burner 17 is a flame regulator 20 which has a reduced end provided with an opening 21 through which the flame is adapted to extend. A finger piece 22 is secured to the flame regulator in any approved manner for applying a regulator to the burner 17. A number of different regulators may be employed in which the discharge orifices 21 are of different sizes in order to vary the size of the flame.

Two means are employed for filling the storage tank or cylinder 10. When it is desired to fill the storage tank 10 by manual means a plug 25 is removed from the opening 26 formed in the head 12 and the liquid is poured into the passage 27 in the head 12 which is in communication with the barrel or storage chamber 10.

When the barrel or storage tank 10 is filled directly from a stationary tank, a flexible hose is connected to a threaded nipple 28 after the cap 29 has been removed. A pipe 30 is connected directly with the nipple 28 and extends downwardly and terminates at 31 adjacent the plug 11 so that when liquid is forced into the barrel 10 it will be directed to the bottom of the tank. As soon as the barrel has been filled, the flexible tubing (not shown) is removed, and the cap 29 is then replaced.

A restricted passage 35 is located in the wall of the chamber 27 and connects the upper end of the barrel 10 with a mixing chamber 15^a. This passage is controlled by means of a needle valve 36 operated by a handle 37. The valve is held in place on the head 12 by means of a threaded sleeve 38 and a bushing 39.

A port 40 connects the mixing chamber 15^a with the atmosphere at one side of a restricted passage 65 in order to supply said mixing chamber with a predetermined quantity of air. The passage 65 connects chamber 15 with 15^a. A second port 41 connects the atmosphere directly with the chamber 15.

A tube 42 connects the mixing chamber 15^a with a block 43 which carries a connection 44 adapted to be placed in communication with compressed air with the pressure of the air being between twenty-five and one hundred

and fifty pounds. A valve 45 controls a passage 46 for regulating the quantity of compressed air which enters the mixing chamber 15^a from the tube 42. The nozzle 5 terminates inwardly of the passage 35 and 40.

The operation of my device is as follows:

After the barrel 10 has been filled with sufficient fuel, the valve 45 is operated to permit compressed air to pass in through the nozzle 50 into the chamber 15^a. The valve 36 is then operated to open position, and as the compressed air passing through the mixing chamber 15^a from the nozzle 50 provides an aspirating effect for forcing fuel from the passage 35 into the mixing chamber 15, air is drawn through the passage 40 to said mixing chamber. As the air and fuel from the mixing chamber enter the burner 17, the mixture is ignited by applying a flame to the slot 18, whereby the flame will pass outwardly from the burner 17 to the atmosphere. The proper sized regulator 20 is applied to the end of the burner 17 and the device is ready for operation.

I claim:

1. A torch comprising a barrel forming a storage chamber for fuel, a head on one end of the barrel provided with a supply chamber in communication with the barrel, the head having a mixing chamber, a valve controlled fuel inlet port between the mixing chamber and the supply chamber, a tube located axially of the barrel, one end of the tube projecting from the barrel, a burner on said end of the tube, the other end of the tube being in communication with the mixing chamber, the mixing chamber having ports connecting said chamber with the atmosphere, a nozzle projecting into the mixing chamber adjacent the fuel inlet port and connected with a source of compressed air.

2. A torch comprising a barrel forming a storage chamber for fuel, a head on one end of the barrel provided with a supply chamber in communication with the barrel, the head having a mixing chamber, a valve controlled fuel inlet port between the mixing chamber and the supply chamber, a tube located axially of the barrel, one end of the tube projecting from the barrel, a burner on said end of the tube, the other end of the tube being in communication with the mixing chamber, said mixing chamber having ports connecting the chamber with the atmosphere, means for directing a stream of air under pressure past the fuel inlet port and the air ports in the chamber.

3. A torch comprising a barrel forming a storage chamber for fuel, one end of the barrel being provided with a mixing chamber and a supply chamber, the supply chamber being in communication with the barrel, a valve controlled fuel inlet port between the mixing chamber and the supply chamber, a tube located axially of the barrel, one end of

the tube projecting from the barrel, a burner on said end of the tube, the other end of the tube being in communication with the mixing chamber, the mixing chamber having ports connecting said chamber with the atmosphere, a nozzle projecting into the mixing chamber adjacent the fuel inlet port and connected with a source of compressed air.

4. A torch comprising a barrel forming a storage chamber for fuel, one end of the barrel being provided with a mixing chamber and a supply chamber, the supply chamber being in communication with the barrel, a valve controlled fuel inlet port between the mixing chamber and the supply chamber, a tube located axially of the barrel, one end of the tube projecting from the barrel, a burner on said end of the tube, the other end of the tube being in communication with the mixing chamber, said mixing chamber having ports connecting the chamber with the atmosphere, means for directing a stream of air under pressure past the fuel inlet port and the air ports.

5. A torch comprising a barrel having its opposite ends closed, one end of the barrel provided with a mixing chamber and a fuel supply chamber in communication with the barrel, a valve controlled fuel inlet port between the mixing chamber and the supply chamber, a tube extending from the mixing chamber through the barrel and terminating beyond the opposite end of the barrel, a burner on the last mentioned end of the tube, means for supplying atmospheric air to the mixing chamber, and means for creating an aspirating effect adjacent the valve controlled fuel inlet port and the means for supplying atmospheric air.
